WELTING

Harold A. Osborne, Swampscott, Mass., assignor
to United Shoe Machinery Corporation, Paterson, N. J., a corporation of New Jersey

Application January 13, 1932. Serial No. 586,387

4 Claims. (Cl. 36—78)

This invention relates to improvements in welt-
ing and is disclosed herein, for the sake of illus-
tration, with respect to weltting particularly
adapted for use in the manufacture of that type
5 of welted shoe in which the outsole is secured
to the welt of the shoe by cement in place of the
usual stitching.

It is usual in manufacturing welted shoes the
soles of which are cement attached to perform
10 the lasting, weltting and inseam trimming opera-
tions in substantially the same manner as in the
manufacture of Goodyear Welt shoes using, how-
ever, in many instances a weltting both lighter and
thinner than is ordinarily used even in the lighter
15 weights of Goodyear Welt shoes. After the in-
seam trimming operation the welt may be beaten
and the inseam rolled. Then the sole-engaging
surface of the welt and the trimmed edges result-
ing from the inseam trimming operation are
20 roughened to prepare those surfaces for the re-
ception of pyroxylin cement by means of which
the sole is to be attached. The somewhat con-
cave form in which the weltting is held by the
inseam at times interferes, however, with the
25 effective roughing of the portion of the surface
of the weltting immediately adjacent to the in-
seam and this reduces the effectiveness of the
bond between the cement and the leather of the
weltting.

30 It is, accordingly, an object of the present in-
vention to overcome the difficulty just mentioned
and this is done, as herein disclosed, by pre-
roughening the weltting, that is by roughening
the weltting before it is incorporated in the shoe.
35 Preferably, and as illustrated herein, the weltting
is roughened while in long lengths and before it is
supplied to the weltter who stitches it to the lasted
shoes. This not only insures that the portion of
the welt immediately adjacent to the stitches of
40 the inseam will be properly roughened but re-
duces substantially the labor of the roughening
operation which must be performed after the
welt has been attached and the shoe inseam
trimmed since it is only necessary then to roughen
45 the freshly cut surfaces resulting from the in-
seam trimming operation and as these are both
definitely defined and solid they can be rough-
ened very easily and without the necessity of in-
corporating in the roughening machine a sup-
50 port for the welt.

Accordingly, my invention comprises an article of
manufacture consisting of pre-roughened welt-
ting, as hereinafter more fully disclosed.

With the above and other objects in view the
55 invention will now be described with reference to

the accompanying drawing and pointed out in
the claims.

The drawing illustrates somewhat diagram-
matically the production of pre-roughened welt-
ting.

60 The weltting illustrated in the drawing com-
prises a strip 10 of leather having continuous,
substantially straight, parallel edges 12 and 14,
a plane grain surface 16 and a plane flesh sur-
face 18 parallel thereto, the latter being provided
65 near the edge of the weltting with a shallow stitch
receiving groove 20. While the dimensions of the
weltting would naturally be varied in accordance
with the type of shoe in which it is to be used,
preferred dimensions of weltting for women's light-
70 weight welted shoes having cement-attached soles
are about $\frac{5}{16}$ of an inch wide and $\frac{1}{4}$ of an inch
thick or a little less, with the center of the groove
about $\frac{1}{8}$ of an inch from the edge of the welt-
ting.

75 When the welt is stitched to the lasted shoe
upper and insole the grain surface of the weltting
engages the shoe upper and the sole, when it is
attached, engages the flesh surface of the welt-
ting.

80 It is usual in the manufacture of welted shoes
having cement-attached soles to last the shoe up-
per to a ribbed or lipped insole in substantially
the same manner as in the manufacture of Good-
year Welt shoes and then to stitch the weltting
85 to the marginal portion of the lasted upper and
to the lip or rib of the insole. After this the
surplus portion of the margin of the upper and
of the lip or rib of the insole, as well as the
edge portion of the welt adjacent to the upper,
90 are trimmed off by the usual inseam trimming
operation as in the manufacture of Goodyear
Welt shoes. Then the welt may be beaten and
slashed, if desired, by the usual welt beating and
slashing machine and the inseam rolled by a ma-
95 chine of the character commonly used for level-
ing Goodyear Welt shoes after which the usual
bottom filler may be applied in the space inside
of the rib or lip at the forepart of the insole. The
welt of the shoe and the edges of stock produced
100 by the inseam trimming operation are then
roughened and coated with pyroxylin cement.
In spite of the welt beating and rolling opera-
tions the welt cannot be depended upon to lie
entirely flat. Particularly, there is likely to be
105 a slight concavity where the welt is pulled in-
wardly by the inseam toward the shoe upper and
the rib or lip of the insole, and this concavity,
together with the slight projection of the stitches
of the inseam, tends to protect the portion of the

110

- welt immediately adjacent to the inseam from the roughening operation and, accordingly, to interfere with the formation of the best kind of bond between the welt and the pyroxylin cement.
- 5 To obviate this condition I propose to roughen the welt before it is attached to the shoe and one way of doing this is illustrated somewhat diagrammatically in the drawing. The welt 10, as illustrated, is supported by a roll or wheel 22 as it is drawn past a rotating wire brush 24 mounted on a shaft 26 which may be driven in any suitable fashion. As illustrated, the wire brush 24 rotates transversely of the welting so that the marks made by the wires of the brush as 15 the brush roughens the welt appear as approximately parallel lines, indicated at 28 in the drawing, extending across the welt from one edge to the other. This treatment picks up or raises the fibre of the welt thereby separating the fibres 20 and leaving the surface of the welt in the best sort of condition for the reception of pyroxylin cement. The entire flesh surface of the welt, except that portion of the surface occupied by the stitch receiving groove, may thus be roughened.
- 25 It should be understood that the welt may be fed and guided by any suitable means as it is roughened. Moreover, it is obvious that the roughening, which is preferably done when the manufacture of the welting is otherwise substantially completed, may be performed in other ways than as illustrated. It may be performed by a wire brush operating lengthwise instead of transversely of the welt. Or it may be performed by other means, such as abrasive or buffing tools; 30 or by a knife or group of knives arranged to cut a series of fine, closely spaced grooves in the welt; or by punch-like tools; or by tools which pick at the surface of the welting. Moreover, it is not essential, in all aspects of the invention, that the 35 welt be grooved.
- While the drawing illustrates a pre-roughening of the entire flesh or sole-engaging face of the welt strip, except the stitch receiving groove, it will be clear that it is not essential that 40 this entire area be roughened since the inner edge of the welt adjacent to the stitch receiving groove is later removed when the inseam trimming operation is performed on the welted shoe.
- The use of pre-roughened welting in the 45 manufacture of shoes the soles of which are cement attached not only assures that the portions of the welt immediately adjacent to the inseam will be properly roughened but greatly facilitates the performance of the roughening operation which must be done after the welt has been 50 attached and the shoe inseam trimmed since it is only necessary then to roughen the freshly cut surface resulting from the inseam trimming operation. Whatever roughening is done on the 55 flesh surface of the welting outside the trimmed
- inseam portion is merely a re-roughening, and it is not necessary to take care that this re-roughening extends over the whole or any substantial part of the untrimmed portion of the welt lying outside the trimmed inseam portion. As the 60 surfaces resulting from the inseam trimming operation are both definitely defined and solid they can be roughened with a minimum of care and labor.
- The manufacture of shoes in accordance with 65 my improved method may be completed by the methods commonly used in the manufacture of welted shoes having cement-attached soles. That is to say, cement is applied to the roughened marginal portion of the outsole and after 70 that cement, as well as the cement on the welt and the edges resulting from the inseam trimming operation, has dried, the cement on one or both of those surfaces is cut with a suitable solvent, the sole applied to the shoe and the shoe 75 and sole maintained under pressure while the cement sets.
- Having thus described my invention what I 80 claim as new and desire to secure by Letters Patent of the United States is:
1. As an article of manufacture, narrow light-weight welting not over about $\frac{1}{16}$ of an inch wide and not over about $\frac{1}{4}$ of an inch thick for use in making shoes having cement attached 85 soles, having its entire flesh and grain surfaces substantially parallel and its sole engaging surface roughened over its whole area to receive sole 90 attaching cement.
2. As an article of manufacture, narrow light-weight leather welting for use in making shoes 95 having cement attached soles, having its flesh surface provided with a shallow groove and roughened over substantially its entire area, including those portions immediately adjacent to and on both sides of the groove, to receive sole attaching cement.
3. As an article of manufacture, narrow light-weight leather welting for use in making welted 105 shoes having cement-attached outsoles, said welting having its sole engaging face buffed whereby 110 its fibres are raised and separated so as to provide a roughened surface for the reception of cement.
4. As an article of manufacture, narrow light-weight grain-faced leather welting for use in 115 making welted shoes having cement-attached outsoles, said welting having its flesh face provided with a shallow stitch-receiving groove near one edge and having the fibres of the sole-engaging area between said groove and the other 120 edge lifted and separated to enhance the cement retaining quality of said sole-engaging area.

HAROLD A. OSBORNE.
